UNITED STATES PATENT OFFICE.

ALBEN E. LUNDELL AND ARTHUR B. SPERRY, OF NEW YORK, N. Y., ASSIGNEES TO
WESTERN ELECTRIC COMPANY, INCORPORATED, OF NEW YORK, N. Y., A CORPORATION
OF NEW YORK.

PRINTING TELEGRAPHY.

Application filed December 21, 1920. Serial No. 432,172.

To all whom it may concern:

Be it known that we, ALBEN E. LUNDELL and ARTHUR B. SPERRY, citizens of the United States, residing at New York, in the county of Bronx and State of New York, and New York, in the county of New York and State of New York, respectively, have invented certain new and useful Improvements in Printing Telegraphy, of which the following is a full, clear, concise, and exact description.

This invention relates to printing telegraphy and particularly to a novel arrangement for effecting the operation of a receiving printer.

An object of the present invention is the provision of a system wherein the operation of an automatic telephone impulse sender or calling dial may be recorded by a receiving printer.

For accomplishing the above and other objects, the invention contemplates the provision of a receiving printer in combination with an automatic telephone selector switch responsive to the operation of an impulse sender or calling dial for selecting a combination of contacts in said switch whereby the printer mechanism is operated for recording the actuation of said impulse sender or calling dial.

In the accompanying drawings there is shown an arrangement of connections between an automatic selector switch and a receiving printer in a system embodying the principles of the present invention. In Fig. 1 there is illustrated an automatic sub-station A which is connected to a pair of line conductors to which there is connected a selector switch B. In Fig. 2 a receiving printer is shown diagrammatically and connected with the contacts on the selector switch B. The invention will be more clearly understood after considering the following description taken in conjunction with the accompanying drawings.

The sub-station A may be of any suitable common battery automatic type as shown in Fig. 1, which comprises the usual receiver 5,

switchhook 38, transmitter 39, call bell 40, and condenser 41. Being an automatic sub-station it is also provided with impulse contact springs 8 and 9 and an impulse wheel 7. The impulse wheel carries upon its periphery a number of teeth designed to engage a plunger for effecting the separation of contact springs 8 and 9. Attached to the impulse wheel 7 is a dial (not shown) with finger holes through the medium of which the impulse wheel 7 may be revolved. As the impulse wheel 7 is returned to normal position by a suitable spring (not shown) contacts 8 and 9 will be broken. The number of times which these contact springs are separated depends upon the distance through which the impulse wheel is rotated.

The selector switch B is of the general type of selector switch disclosed in U. S. Letters Patent No. 815,176 issued March 13, 1906 to Keith, Ericson and Ericson. Like all switches of this type the selector is provided with a vertical shaft 43. Mounted on this shaft, at points intermediate its ends, is a pair of brushes 35 and 36. These brushes are arranged to engage contacts arranged in an arcuate bank upon an upward and rotary movement of the shaft 43. In the present invention two banks of terminals are provided, the lower one of which is designed so that the contact brush 35 engages two contacts thereof for each position of the switch, while in the upper bank of terminals the brush 36 engages but one contact for each position of the switch. Associated with the selector switch B is the necessary apparatus, including relays and other mechanical mechanism for effecting the operation of the switch, and since this part of the system is well understood by those skilled in the art, a further description thereof is considered unnecessary here.

Interconnecting the selector switch B and the receiving printer C is a plurality of conductors divided into two groups. One group of these conductors connects the contacts of the respective bank of terminals with the selecting relays and magnets of the printer.

The other group of conductors extends between additional apparatus common to the selector switch mechanism to the apparatus of the printer. A receiving printer of the type adapted to be used for the present invention is disclosed and described in Patent No. 1,113,033 issued to A. F. Dixon July 14, 1914, and since this patent describes in detail such a receiving printer, and especially 10 since the receiving printer per se is not claimed in the present invention, only so much of the system has been shown as will afford a clear understanding of the invention. Obviously, though, other types of receiving printers may be employed other than the one disclosed and claimed in the above referred to patent.

A better understanding of the invention may be obtained from a description of the 20 selection of a particular character and the operation of the system for such a selection will therefore be traced in the following description. Assuming that the subscriber A desires to transmit the digit 4, the 25 impulse wheel 7 will thus be rotated. Upon the return of the impulse wheel 7, contacts 8 and 9 will be separated in accordance with the operation of the impulse wheel 7. The subscriber A, having already removed 30 the receiver 5 from the switchhook, causes the operation of line relay 10, and consequently the slow to release relay 11. Each time contact springs 8 and 9 are separated, line relay 10 deenergizes. Since relay 11 35 is of the slow to release type, it does not have sufficient time to deenergize during the momentary interruption of its circuit at the right-hand contact of line relay 10. Consequently, the engagement of the armature of relay 10 with its normal contact establishes a circuit extending from battery through the vertical magnet 13, relay 12, left-hand armature of relay 11, left-hand armature of relay 14, and the normal contact 40 and armature of relay 10 to ground. The vertical magnet 13 receives four impulses over this circuit and operates to raise the vertical member 43 and brushes carried thereby four steps to a position opposite 45 the fourth row of terminals in each of the contact banks. The relay 12 is energized in series with the vertical magnet 13, but being of the slow to release type, does not have sufficient time to deenergize upon the momentary interruption of its energizing circuit at the contacts of line relay 10. Relay 50 12 upon energizing closes a circuit from battery through the winding of relay 15 off normal contact 33, left-hand contact and armature of relay 16, left-hand alternate contact of relay 12, and the right-hand alternate contact of relay 11 to ground. The closure of the left-hand contact of relay 15 establishes a locking circuit for this relay 55 which extends from battery through the

winding of relay 15 off normal contact 33, left-hand contact and armature of relay 16, right-hand contact of relay 15, right-hand normal contact of relay 16, conductor 44, the right-hand armature, and alternate 70 contact of relay 11 to ground. As a result of the establishment of this locking circuit, relay 15 remains energized after relay 12 releases its armature upon the cessation of the impulses transmitted for the fourth 75 digit. Upon the deenergization of relay 12 a circuit is established extending from battery through rotary off-normal contact 38 winding of rotary magnet 16, right-hand contact and armature of relay 15, normal 80 contact of relay 12, and the right-hand contact of relay 11 to ground. The rotary magnet 16 upon energizing rotates the vertical shaft 43 together with the brushes carried thereby one step. The off-normal contact 38 85 which is shown normally closed, is opened following the rotation of the vertical shaft 43 through a distance equal to one step. The rotary magnet 16 is thereupon prevented from energizing following its release and 90 the consequent reenergization of relay 15. By rotating the springs 35 and 36 contact is made with the contacts in the fourth level of each of the respective banks. The brush 36 like the brush 35 serves to select circuits 95 as is described hereinafter for the operation of predetermined ones of the selecting relays and magnets of the printer mechanism shown in Fig. 2. Rotary magnet 16 in closing its left-hand contact establishes an energizing circuit for relay 14 extending from battery through the winding of relay 15, off normal contact 33, left-hand contact and armature of relay 16, winding of relay 14, and the right-hand armature and contact 100 of relay 11 to ground. Relay 14 in attracting its armatures opens at the right-hand contact thereof the original energizing circuit for relay 12 and the vertical magnet 13 for preventing the false operation of 105 these devices.

Upon the engagement of the brush 35 with contacts 45 and 46 a circuit extending through the left-hand winding of relays 122 and 124 of the printer mechanism is established. Normally, current flows from battery 110 104, left-hand normal contact of clear out relay 180, conductor 106, and the right-hand windings of relays 121, 122, 123, 124, 125 and 126 to ground. The current passing through the windings of these relays is, however, insufficient to cause the initial operation thereof, but serves to assist the operating windings in pulling up the respective armatures, thereby increasing the rapidity 115 of operation. After the relays have once been operated, the current flowing from the battery 104 is sufficient to hold the armatures in their actuated positions. The connection of the brush 35 with contacts 45 and 46 ap- 120

- plies to these terminals a ground connection, and since battery is normally connected with the right-hand windings of relays 122 and 124, these relays will be operated over a circuit extending from battery through the left-hand winding thereof, and the conductors connecting with contacts 45 and 46 of the selector switch B, contact springs 35 to ground at the normal contact of relay 19.
- 10 The selector magnets 132 and 134 are connected in parallel relation with the selecting relays 122 and 124, and will thus be energized over the same circuit as traced for relays 122 and 124. Normally, current flows from battery 104, through the right-hand normal contact of clear out relay 180, holding windings of release magnets 178 and 179, right-hand winding of type selecting magnets 131, 132, 133, 134 and 135, as previously described in connection with the selecting relays, this current is insufficient to initially operate the magnets, but will however retain them actuated after the original operating circuit is severed. Selecting relays 121, 123 and 125 will not be operated at this time, a circuit including the windings of these relays is not established upon the engagement of the brush 35 with the contacts 45 and 46. In the upper bank of terminals 30 of the selector switch B, the fourth level of contacts is not connected. Thus, no effect is produced on the printer circuits. As hereinbefore described, a current normally flows through the right-hand windings of the selecting relays. Consequently, upon the energization of any one thereof, the armatures will be retained in their actuated positions irrespective of the disconnection of the original operating current.
- 40 Following the operation of relay 14, relay 18 is energized over a circuit extending from battery through the winding of relay 15, off normal contact 33, left-hand contact and armature of relay 16, left-hand contact and armature of relay 15, right-hand contact and armature of relay 16, winding of relay 18, winding of relay 19, right-hand armature and contact of relay 14, and the right-hand armature and contact of relay 11 to ground.
- 50 The attraction of the middle armature of relay 18 establishes a circuit extending from battery through the shift magnet 170, conductor 24, middle armature and contact of relay 18, conductor 25, and contact 142 to ground. Shift magnet 170 upon energizing, attracts its armature for shifting the type wheel from a lower to an upper case letter. In order that the type wheel will be retained in this position for a definite number of digits, a locking circuit, therefore, is established upon its energization. This locking circuit extends from battery through the winding of shift magnet 170, contact and armature thereof, and contact 142 to ground.
- 65 Relay 18 in closing its left-hand contact connects a source of battery 47 to the left-hand winding of start relay 126, and the operating windings of release magnets 178 and 179. Start relay 126 and release magnets 178 and 179 are thereupon energized over a circuit 70 extending from battery 47, left-hand contact and armature of relay 18, conductor 37, conductors 140 and 141 in parallel, and the operating winding of relay 126 and release magnets 178 and 179 to ground. Release 75 magnets 178 and 179 attract their armatures, forcing the free ends thereof as described in the previously referred to patent, for allowing the selected type lever 165 to assume a new position, the projecting end thereof being in alignment with the stop member 166. The stop member 166 is carried by the same shaft as the type wheel (not shown). Thus, upon the engagement of this member with the projecting end of the lever 165, the type 80 wheel will be arrested. The operation of the start relay 126 applies through its right-hand contact ground for effecting the operation of start magnet 194. The energizing circuit of the start magnet 194 extends from 85 battery 104, left-hand armature and contact of clear-out relay 180, conductor 108, winding of start magnet 194, conductor 109, right-hand armature and contact of start control relay 192, and the armature and contact of relay 126 to ground. The start magnet 194 thereupon attracts its armature causing the release of the shaft carrying the type wheel (not shown) and the stop member 166. The stop member 166 thereupon 90 rotates in the direction of the arrow, until in engagement with the projecting portion of the selected type lever 165. Upon the engagement of the member 166 with the lever 165 a circuit is established for the printing 95 magnet 105 extending from battery 104, winding of clear-out relay 180, left-hand winding of space locking relay 107, conductor 111, winding of printing magnet 105, stop arm 166, selected type lever 165, conductor 23, and the armature and contact of relay 19 to ground. Printing magnet 105 attracts its armature, forcing a printing hammer (not shown) against the paper, printing 100 the desired character.
- 110 The circuit just traced through the winding of relay 180 causes this relay to attract both its armatures, breaking the holding circuit extending through the selected relays 121, 122, 123, 124 and 125, and the start relay 126. The attraction of the right-hand armature opens the holding circuit of the release magnets 178 and 179, and the type selecting magnets 132, 133, 134 and 135. The opening of the holding circuits of the 115 respective relays and magnets restores the selected mechanism of the printer to its normal position for the reception of further selecting impulses. The closure of the right-hand alternate contact of clear-out 120
- 125 130

relay 180 establishes an energizing circuit for a retractor relay 153 extending from battery 104, right-hand armature and alternate contact of clear-out relay 180, and the winding of retractor relay 153 to ground. The retractor relay 153, upon energizing closes a circuit extending from battery 113, winding of retractor magnet 155, and the right-hand armature of retractor relay 153 to ground. The retractor magnet 155 pulls up its armature (not shown) for causing the release and the restoration of the shaft carrying both the type wheel and the stop member 166 to its normal position. The instant the contact member 166 starts to return to its normal position, the contact between the member 166 is broken. Thus, the circuit for the printing magnet 105 is severed for causing the deenergization of this magnet.

20 The circuit previously traced from battery 104, extending from clear-out relay 180 and the space locking relay 107, also causes the energization and locking up of space locking relay 107. The locking circuit for the space locking relay 107 extends from battery 114, winding of spacing magnet 130, conductor 115, right-hand armature and contact of space locking relay 107, right-hand winding of this relay, and the right-hand normal contact and armature of relay 136 to ground. The space magnet 130 attracts its armature 139, causing the stepping pawl attached thereto to engage the teeth of a ratchet wheel 137, advancing this wheel through the space of one tooth. The ratchet wheel 137 carries a drum 138, upon which is wound, as illustrated in the previously referred to patent, a cord connected to the paper carriage. As this cord is wound upon the drum 138, due to the engagement of the teeth of ratchet wheel 137 by the stepping pawl controlled by spacing magnet 130, the paper carriage will be moved from right to left. The operation of the spacing magnet is insured irrespective of length of the operating impulse, as the armature of the space locking relay 107 is held in its actuated position until the armature 139 of the spacing magnet 130 is attracted a sufficient distance to cause an insulated pin carried at one extremity thereof to engage contact spring 116. The engagement of the insulated pin of contact spring 116 causes the closure of contacts 117 and 55 118. The engagement of contact 117 causes the right-hand winding of space locking relay 107 to be short circuited through conductor 119. Space locking relay 107 thereupon releases its armature, opening the energizing circuit of spacing magnet 130. However, before the spacing magnet 130 is deenergized, a circuit is established upon the engagement of contact spring 118 extending from battery 120, conductor 27, left-hand normal contact and armature of relay 21, and the winding of relay 22 to ground. Relay 22 upon energizing closes at its contact an operating circuit for relay 21 extending from battery through the winding of relay 15, off normal contact 33, left-hand contact and armature of relay 16, left-hand armature and contact of relay 15, right-hand contact and armature of relay 16, winding of relay 21, left-hand contact and armature of relay 22, off normal contact 34 75 winding of release magnet 17, winding of relay 19, left-hand armature of relay 14, and the right-hand armature of relay 11 to ground. Relay 21 upon attracting its armatures, closes at the right-hand contact thereof of a locking circuit extending from battery through the winding of relay 15, off normal contact of relay 33, left-hand contact and armature of relay 16, left-hand armature and contact of relay 15, right-hand contact 80 and armature of relay 16, winding of relay 21, right-hand contact and armature of relay 21, off normal contact 34, winding of release magnet 17, winding of relay 19, right-hand armature and contact of relay 90 14, and the right-hand armature and contact of relay 11 to ground. The attraction of the left-hand armature of relay 21 opens the operating circuit of relay 22, which thereupon releases its armature. The circuit just traced includes the winding of release magnet 17 of the selector switch B, which in energizing attracts its armature for causing the restoration of the selector switch mechanism to normal.

95 Since the subscriber's number comprises a series of digits, usually four in number, it is desired to equip the printer mechanism with means whereby the type carriage, after printing four digits, will be automatically restored to normal. In the present invention this is accomplished by mounting a set of contact springs 142 and 143 in close proximity to the drum 138. Secured to the drum 138 is an insulated pin 144. Pin 144 is thus advanced for each movement of the drum 138, and since the contact springs 142 and 143 are arranged to be engaged by the pin 144 after the drum 148 has been advanced four steps, contact spring 142 will thus disengage its associated contact while contact spring 143 will be brought into engagement with its contact. The disengagement of contact 142 causes the deenergization and release of shift magnet 170. Upon the engagement of contact 143 with its associated contact, a circuit is established extending from battery 145 through contact spring 143, conductor 146, winding of line feed relay 110, left hand armature and contact of selecting relay 123, contact and armature of relay 125, winding of relay 192, and the armature and contact of relay 126 to ground. Line feed relay 110 upon energizing closes through its contact a circuit for the line feed magnet 130

112 extending from battery through the right-hand contact and armature of relay 18, conductor 26, winding of line feed magnet 112, conductor 148, and the armature 5 and contact of line feed relay 110 to ground. Line feed magnet 112 attracting its armatures closes at its right-hand contact an energizing circuit for carriage return relay 191. This energizing circuit extends from 10 battery through the normal contacts and armatures of the selected relay 121, 122 and 123, conductor 150, winding of relay 136, right-hand winding of carriage return relay 191, and the right-hand contact and armature of line feed magnet 112 to ground. Upon the energization of relay 136, a locking circuit for the line feed magnet 112 is established extending from battery through 15 the right-hand contact of relay 18, conductor 26, winding of line feed magnet 112, left-hand contact and armature of line feed magnet 112, and the alternate contact and armature of relay 136 to ground. Carriage return relay 190 closes at its armature a circuit 20 for the carriage return magnet 196. The energizing circuit for the carriage return magnet 196 extends from battery through the winding of the carriage return magnet 196, alternate contact of carriage return relay 25 191, and the left-hand winding of carriage return relay 191 and contact 151 in parallel to ground. The energization of the carriage return magnet 196 causes the disengagement 30 of a holding pawl (not shown) associated with the ratchet wheel 137 to be released. The disengagement of the holding pawl under the control of the carriage return magnet 196 thereupon releases the ratchet wheel 35 197, which is restored to normal due to the action of a spring (not shown). As the limit of the carriage return is reached, the pin 144, engages contact spring 151, causing the closure of the contact associated therewith and the short circuiting of the holding 40 winding of the carriage return relay 191. The carriage return relay 191 is thereupon deenergized. Consequently, the carriage return magnet 196 is caused to release the holding pawl controlled thereby for effecting 45 the engagement thereof with the ratchet wheel 137, as the paper carriage is stepped forward for a line of print. The energization of the line feed magnet also causes the operation of a suitable stepping pawl for 50 shifting the paper or other printing medium to a new line.

For the selection of certain combinations of groups of the selecting relays and magnets of the printer mechanism shown in Fig. 60 2, it is necessary, for certain positions of the vertical shaft 43, that a larger number of circuits be selected than is possible with the use of the double and single brush arrangement as shown at 35 and 36. Thus, when 65 the brushes 35 and 36 are on the first level

or first set of contacts, relay 20 is energized for closing through its contacts energizing circuits for the selecting relays 123 and 125 in addition to those established through the brushes 35 and 36 as well as the selector magnets corresponding thereto. 70

From the above description it is evident that the present invention provides a system whereby a printed record may be made of the operation of an automatic telephone substation dial. By means of such an arrangement it is possible to determine whether it is psychologically possible for the ordinary telephone user to set up a connection involving more than four digits. It is of course 80 understood that the mechanism may be rearranged for enabling the printing of a larger number of digits without departing from the spirit and scope of the invention. 85

What is claimed is:

1. In combination, a telephone line extending between a central office and a substation, telephone equipment located at the substation and connected with the line including a calling dial, a step-by-step selector switch at the central station responsive to impulses transmitted over said line due to the operation of the calling dial, and a receiving printer comprising a plurality of selector magnets responsive to the positioning of said selector switch in accordance with the operation of said calling dial, a printing magnet, and means associated with said selector switch and operated due to the positioning thereof for conditioning an energizing circuit for said printing magnet whereby the operation of said calling dial will be recorded. 95

2. In combination, a telephone line extending between a central office and a substation, telephone equipment located at the substation and connected with the line including a calling dial, a step-by-step selector switch at the central station responsive to impulses transmitted over said line due to the operation of the calling dial, a receiving printer comprising a plurality of selector magnets responsive to the positioning of said selector switch in accordance with the operation of said calling dial, means for causing the printing of the character selected through the operation of said selector magnets, and means controlled by the printer mechanism for causing the restoration of the selector switch at the central station to 110 normal following the printing of the selected character. 115

3. In combination, a telephone line extending between a substation and a central office, telephone equipment located at the substation including a calling dial, a step by step selector switch at the central office having a plurality of contacts and responsive to impulses transmitted over said line due 125 to the operation of the calling dial to see. 130

lect predetermined ones of said contacts, a plurality of local circuits connected to the contacts of said selector switch, and a receiving printer having its selecting mechanisms connected in said local circuits and operated directly through the contacts of said selector switch for recording the digits

In witness whereof we hereunto subscribe our names this 17th day of December, A. D. 1920.

ALBEN E. LUNDELL.
ARTHUR B. SPERRY.
